18 Claims. (Cl. 315—39)

1

This invention relates generally to magnetron microwave generators and more particularly to improved means for frequency modulating or amplitude modulating microwave generators of the magnetron type.

In its basic form, the conventional magnetron microwave generator comprises a centrally disposed thermionic cathode surrounded by a plurality of radially extending anode vanes or segments which form a plurality of radially extending anode cavity resonators tuned to the operating microwave frequency. A source of constant operating potential is connected between the cathode and anode in a manner whereby the anode is at a positive direct-current potential with respect to the cathode. A substantially constant intensity magnetic field is applied axially to the cathode-anode chamber. Electrical charges accumulate on the anode vane tips adjacent to the cathode, resulting in oscillatory electric fields, hereinafter termed electric fields, in the anode cavity resonators which fields interact with the electrons travelling in cycloidal paths from the cathode to the anode, thus abstracting energy from the travelling electrons and producing sustained oscillations at the operating microwave frequency. An inverted variation of the conventional magnetron structure comprises a centrally disposed gear-shaped anode having a plurality of radially extending peripheral anode cavities, the anode structure being surrounded by a cylindrical electron-emissive cathode, and the entire structure being subjected to an axial constant intensity magnetic field.

In accordance with the instant invention, the geometries of the conventional and inverted magnetron generators described heretofore are combined in a manner whereby a centrally disposed cathode and surrounding radially disposed anode vanes comprise a magnetron generator, and a peripherally disposed ring-shaped second cathode surrounds an axially-extended portion of the anode, the entire structure being subjected to a constant intensity magnetic field extending transverse to the path of electrons from the cathodes to the anode. The anode is positively biased with respect to both of the cathodes whereby the central cathode and intermediate anode structure comprise a conventional magnetron generator. The ring-shaped second cathode, surrounding the extended portion of the anode, provides supplementary electron emission which is caused to interact with the electric fields established between the anode cavity resonator vanes in a manner whereby the frequency or the amplitude, or

2

both, of the generated oscillations may be modulated. A shield or other device disposed between the second cathode and the remaining portion of the anode structure, and biased negatively with respect to the anode structure, causes the electron emission from the second cathode to be directed substantially only to the extended portion of the anode structure, and to be effectively shielded from the remainder of the anode structure.

10. If desired, the simple second cathode and cathode shield structure may be replaced by a more elaborate ring-shaped modulating electron gun structure including a control grid and, if desired, additional electron beam-forming grids, whereby electrons emitted from the inside surface of the modulating electron gun ring are directed substantially only to the extended anode cavity vane tips.

20. When a novel magnetron of the type described is operated with suitable magnetic field and direct-current operating potentials applied between the anode and the two cathodes, microwave oscillations will result, and electric fields of the desired mode of operation will be established in the cavity resonators between the anode vanes. When an electric field is established inside the resonator, an electric field of the same angular velocity will exist between the adjacent extended

30. anode vane tips on the outside thereof, in the space between the vane tips and the modulating outer cathode. If, during oscillation, a direct-current potential is impressed between the modulating cathode and the anode vanes, then, due to action of the magnetic field, the electrons emitted by the modulating cathode will travel toward the vane tips in cycloidal paths and interact with the outside vane tip electric field and induce currents in the vane structures. The

40. axial magnetic field, the geometry of the tube structure, and the direct-current operating potentials applied thereto, can be so adjusted that these induced currents are out-of-phase with the normal circulating currents in the vanes, and a frequency shift, or a change in oscillation amplitude, or both, can be obtained. All of the axially disposed anode cavity resonators are subjected to the same interaction simultaneously so that electric field symmetry is preserved.

50. A modification of the devices described heretofore utilizes a plurality of effectively axially-elongated parallel-disposed anode cavity resonators, as distinguished from the radially-extending cavity resonators, wherein the parallel-disposed resonators simulate a cylindrical shell.

The presence of the central cathode and the axial magnetic field will cause this system to generate microwave oscillations of the frequency determined by the proportions of the parallel resonators. A travelling electric field will exist on the outside tips of the anode vanes, said field having the same angular velocity as the internal electric field. Electrons drawn to the resonator vanes from the outer modulating cathode will interact with the outer electric field, thus providing frequency or amplitude modulation of the generated oscillations.

Among the objects of the invention are to provide improved means for modulating magnetron microwave generators. Another object is to provide improved means for providing frequency modulation, amplitude modulation, or both types of modulation, of microwave oscillations generated under conditions of magnetron operation. A further object of the invention is to provide an improved microwave magnetron structure comprising a central cathode, an intermediate anode structure having a plurality of radially disposed anode vanes, and an external cylindrical modulating electron beam generating structure operative upon the adjacent anode vane tips. Another object of the invention is to provide an improved microwave generator including means for modulating either the frequency or the amplitude of the generating microwave oscillations wherein the intensity of an axial magnetic field is adjusted to provide efficient magnetron generator operation, and the desired type of signal modulation of the generated oscillations.

The invention will be described in greater detail by reference to the accompanying drawings of which Figure 1 is a schematic diagram of a conventional magnetron generator; Figure 2 is a schematic diagram of an inverted magnetron microwave generator; Figure 3 is a cross-sectional, elevational, partially-schematic view of a first embodiment of the instant invention taken along the section line III—III of Fig. 4; Figure 4 is a plan, cross-sectional, partially-schematic view, taken along the section line IV—IV of Figure 3, of said first embodiment of the invention; Figure 5 is a fragmentary plan view, taken along the section line IV—IV of Figure 3, of a modification of said first embodiment of the invention; Figure 6 is a perspective fragmentary view of a second embodiment of the invention; Figure 7 is a cross-sectional, elevational, partly sectional view of a preferred modification of said first embodiment of the invention; Figure 8 is a side elevational cross-sectional view taken along the section line VIII—VIII of Figure 7; and Figure 9 is a plan cross-sectional view taken along the section line IX—IX of Figure 7. Similar reference characters are applied to similar elements throughout the drawings.

Referring to the drawings, Figure 1 illustrates schematically a conventional magnetron structure comprising a central elongated electron-emissive cathode 1 surrounded by a plurality of radial anode vanes 3 and enclosed within an evacuated conductive envelope 5 to which the radial anode vanes are connected. A source of direct-current operating potential is connected between anode and cathode in a manner whereby the anode is positively biased with respect to the cathode. An axial, constant intensity, magnetic field indicated by the designation 7 is applied to the device from an external magnet structure not shown. The operation of such conventional magnetrons is well known in the art

70
75

and will not be described in detail herein. Microwave energy for a load, not shown, is derived from a coupling loop 9 coupled into one of the anode cavity resonators 11 formed by the radial anode vanes 3 and the conductive outer wall 5. The anode cavity resonators are tuned to resonate in radial modes at the desired operating frequency. The coupling loop 9 is coupled through a coaxial line 13 to the load.

Figure 2 illustrates an inverted modification of the standard magnetron generator of Figure 1, wherein the elements are inter-changed, the anode comprising a central cylindrical element 15 having a plurality of radially extending vanes 3', the anode structure being surrounded by an evacuated metallic cylindrical envelope 5'. The inner surface of the cylindrical envelope 5' supports a ring-shaped cathode 1' which may be either directly or indirectly heated. The output coupling loop 9' is coupled through a suitable aperture 17 in the anode structure 15 to an external load not shown. The spaces between adjacent anode vanes 3' comprise the anode resonators which are tuned to resonate in radial modes at the operating microwave frequency. In either of the devices of Figures 1 and 2, alternate anode vane tips may be connected together by one or more pairs of concentric anode vane connector rings in accordance with known technique, and as shown in Figures 3, 4 and 5.

Referring to Figures 3 and 4, a combination of the structures of Figures 1 and 2 is employed, according to the invention, to provide a microwave magnetron generator having a modulating electron-emissive structure disposed externally of a portion of the anode vane tips. The central cathode 1, supported by suitable means not shown, is surrounded by a plurality of radially extending anode vanes 3 enclosed within an evacuated metallic envelope 5 as in the device of Figure 1. The anode vanes define therebetween a plurality of anode cavity resonators tuned to resonate in radial modes at the operating frequency. The inner ends or vane tips 19 of the anode vanes 3 are extended axially, upwardly in Fig. 3, and alternate vanes are connected together by a pair of concentric rings 21. Similar rings 23 connect together alternate ones of the anode vanes 3 at the lower ends thereof. The projecting vane tips 19 and rings 21 are surrounded by a ring-shaped second cathode 25 shielded from the remainder of the anode vane structures by a ring-shaped shield 27 which is maintained at the same potential as the second cathode 25, or, may be negatively biased with respect thereto. The anode vanes 3 are positively biased with respect to the central cathode 1 and with respect to the outer or modulating cathode 25, so that the rings 21 serve as collector rings. A source of modulating signals is connected between the outer cathode 25 and the anode vane structure to vary the reactive or conductive effect of the modulating electron beam emission in response to the modulating signals, as described heretofore. The device is subjected to an axial magnetic field, as indicated at 7, the intensity of which may be adjusted to provide maximum magnetron generator efficiency and also the desired type and degree of modulation of the generated oscillations as will be described in greater detail hereinafter. The different magnetic field intensities applied to different portions of the device may be provided by tapering the pole pieces of the axial magnetic field structure, not shown, in accordance with known tech-

nique. Modulated microwaves may be derived from the device by means of the coupling loop 9 and coaxial transmission line 13 coupling the device to a load, not shown.

Figure 5 discloses a modification of the device described by reference to Figures 3 and 4 wherein the modulating electron beam structure includes a control grid 29 and one or more beam forming grids 31 having a plurality of apertures 33 aligned with the several extended anode vane tips 19. By biasing the beam forming grid 31 positively with respect to the cathode 25, the electron emission therefrom is more efficiently directed to the extended anode vane tips 19 than in Figs. 3 and 4. The modulating signal source is connected between the control grid 29 and the cathode 25 to modulate the electron emission to the extended anode vane tips 19. The concentric cathode, control grid and beam forming grids may be supported in any desired manner adjacent to the upwardly projecting anode vane tips 19 and may be of any suitable design to provide the desired focussing of the modulating electron emission to concentrate said emission on the adjacent anode vane tips.

The device illustrated in Figure 6 is similar to that described heretofore by reference to Figures 3 and 4 with the exception that the central cathode 1 does not extend the full axial length of the anode vanes 3, and the vanes 3" are extended axially of the device to provide effectively axially-elongated parallel disposed resonators resonating in longitudinal or axial modes. The modulating electron beam structure including the cathode 25 surrounds the upper portion of the anode vanes 3" concentric with the central cathode 1. The ends of the anode vanes 3" may be alternately connected together by vane connecting rings as described heretofore.

Referring to Figures 7, 8 and 9, a preferred embodiment of the invention utilizes a modified RCA type 2J41 microwave magnetron comprising an evacuated metallic envelope 5 in which is enclosed a pair of magnetic iron pole pieces 41, 43, between which are positioned an axially disposed indirectly heated cathode 1 and a coaxial assembly of radially disposed anode vanes 3 supported by a heavy transverse metallic block 45 mounted on the base 53 of the envelope 5. An axially adjustable apertured flat tuning member 47 is disposed adjacent to one end of the anode cavity resonator assembly. The tuning member 47 is fastened to the block 45 at the point 49 and is axially adjustable over a limited range by movement of the pin 51 secured to the opposite end thereof. The pin 51 is flexibly secured to the base 53 of the tube envelope, and its location is determined by a set-screw 55 in a block 57 on the base 53. The radially disposed anode vanes and the block 45 are cut away as indicated at 59 to provide a plurality of anode vane tips 19 around which is disposed a ring-shaped modulating electron beam cathode 25. The modulating cathode 25 is surrounded on the three sides removed from the vane tips 19 by a hollow ring-shaped shield 28 which shields the modulating beam cathode from the remainder of the anode structure and from the magnetic pole pieces 41 and 43.

The pole pieces 41, 43 are supported on the transverse block 45 by heavy cylindrical insulators 61, 63 and transverse brackets 65, 67. Separate terminals are brought out through the evacuated envelope for the central cathode and heater connections, as well as for the modulating

beam cathode 25 and, if desired, for the cathode shield 28. If desired, the modulating cathode 25 and shield 28 may be connected together inside of the tube envelope. The anode vanes 3 are alternately strapped together, at the end remote from the modulating beam cathode 25, by a pair of concentric rings 23. Modulated microwave energy is applied to a load, not shown, by means of a coaxial transmission line 13 extending through the envelope and terminated in a coupling loop 9 disposed within one of the anode cavity resonators. The external magnet structure, not shown, for supplying the constant intensity axial magnetic field is closely fitted to the device adjacent to the outer ends of the magnetic pole pieces 41, 43 whereby an axial magnetic field indicated by the arrows 7 is provided.

The operation of the device described in Figures 6, 7 and 8 is in all essential respects similar to that described heretofore with respect to the device illustrated in Figures 3 and 4.

It has long been known that as a magnetron of the multicavity type with a central cathode is turned on, the presence of space charges in the space between the cathode and vane tips produces an electronic admittance in shunt with the cavities which will change the frequency of the magnetron as it operates. This is known as "pushing" and the amount of pushing will in general increase as the current is increased for most ranges of application. See "Stabilized Magnetron for Beacon Service" by Donal, Cuccia and Brown, RCA Review, June 1947.

Pushing is due to the fact that as the electrons circle around the central cathode with increasing radius as they proceed to the vane tips due to the radial direct current field they will interact with the inner electric fields between the anode vanes E_1 in Figure 4. Energy will be exchanged, some electrons giving up energy to the field E_1 , some removing energy from the field E_1 . This exchange will go on all the time and, in a high efficiency magnetron, the electrons will bunch as they approach the vane tips and will eventually give up their energy. As this energy exchange progresses, the interactions will appear to have susceptance as seen by the cavities to an extent dependent upon the net energy given up and then extracted from the field E_1 during a complete cycle of oscillation.

"Pushing" in general is undesirable but tolerable and is inherent in normal magnetrons. In this invention, a structure base on an inverted magnetron is incorporated into a normal structure and will provide a "pushing" mechanism which is independent of the central interaction space. Essentially speaking, the electrons emitted from the modulating cathode will, due to a direct current field between the modulating cathode and the vane tips, travel toward the vane tips and interact with the outer electric field, E_2 in Fig. 4, which are produced by the oscillations due to electrons from the central cathode in normal magnetron fashion, and either frequency modulation or amplitude modulation can be obtained. This is because as the electrons leave the modulating cathode in purely random fashion they will react with the outer fields E_2 . If they are in the presence of a magnetic field of suitable intensity and a suitable direct current field, they will bunch after repeated interactions and absorb energy from the field E_2 , and amplitude modulation will take place. If, using suitable magnetic field and direct current field, they interact with E_2 so that no net energy exchange takes place during a cycle

7 of oscillation, the vane tips will see a pure reactive load and frequency modulation only will take place.

Some of the advantages of the arrangements described for accomplishing frequency modulation and amplitude modulation are:

1. A control grid responsive to modulation signals may be employed with the outer cathode.

2. The outer cathode is capable of large energizing current due to its relatively large structure.

3. Interactions between the modulating electrons and the anode vane tips are independent of the interactions producing oscillations which are taking place between the central cathode and the vane tips.

As the electrons leave the outer cathode, they will not proceed directly to the vane tips, due to the presence of the magnetic field. They will travel in such fashion as to result in each electron having both an r and a θ directed velocity where r is a radius and θ is an azimuthal angle.

While the general operational characteristics of the various embodiments of the invention have been described heretofore, the mathematical relations between the various operating parameters may be defined as follows:

The fields E_1 and E_2 produced by charges at the vane tips may be written, in terms of their r and θ directed components,

$$E_{1r}, E_{1\theta}, E_{2r}, E_{2\theta}$$

as a set of Fourier series as follows:

$$(1) \quad E_{1r}(r, \theta, t) = E_0 \sum_{l=-\infty}^{l=\infty} \left(g_1 \right)_l^n \frac{J'_{nl}(K_n r_1)}{J'_{nl}(K_n r_{a_1})} \cos(nl\theta - \omega_n t)$$

$$(2) \quad E_{1\theta}(r, \theta, t) = \frac{nE_0}{K_n r_1} \sum_{l=-\infty}^{l=\infty} \left(g_1 \right)_l^n \frac{J'_{nl}(K_n r_1)}{J'_{nl}(K_n r_{a_1})} \sin(nl\theta - \omega_n t) \quad 40$$

$$(3) \quad E_{2\theta}(r, \theta, t) = E_0 \sum_{l=-\infty}^{l=\infty} \left(g_2 \right)_l^n [LJ'_{nl}(K_n r_2) + MN'_{nl}(K_n r_2)] \cos(nl\theta - \omega_n t) \quad 45$$

$$(4) \quad E_{2r}(r, \theta, t) = \frac{nE_0}{K_n r_2} \sum_{l=-\infty}^{l=\infty} l \left(g_2 \right)_l^n [LJ'_{nl}(K_n r^2) + MN'_{nl}(K_n r_2)] \sin(nl\theta - \omega_n t)$$

where

E_0 is the electric field between the vane tips (volts).

$n = \frac{N}{2}$ where N is the number of cavities of the magnetron which is to operate in the preferred π mode.

r_{a_1} = radius to inner vane tip edge.

$0 < r_1 < r_{a_1}$

τ = the lth Fourier component of the field.

$J_{nl}(K_n r_1)$ = Bessel function of first kind.

$N'_{nl}(K_n r_2)$ = Neumann function (Bessel function of second kind).

K_n is defined by $K_n^2 = \frac{\omega_n^2}{C^2} = \mu \epsilon \omega_n^2$.

ϵ is the dielectric constant of the interaction space

ω_n is the angular velocity of nth component.

$$(g_1)_l^n = \frac{1}{2\pi E_0} \int_0^{2\pi} E_0(r_{a_1}, \theta) e^{-i\tau l\theta} d\theta$$

$$(g_2)_l^n = \frac{1}{2\pi E_0} \int_0^{2\pi} E_0(r_{a_2}, \theta) e^{-i\tau l\theta} d\theta$$

r_{a_2} = radius to outer vane tip.

r_c = radius to outer cathode.

$M = -$

$$J'_{nl}(K_n r_{a_2}) N'_{nl}(K_n r_c) - J'_{nl}(K_n r_c) N'_{nl}(K_n r_{a_2}) \\ L = \frac{+ N'_{nl}(K_n r_c)}{J'_{nl}(K_n r_{a_2}) N'_{nl}(K_n r_c) - J'_{nl}(K_n r_c) N'_{nl}(K_n r_{a_2})} \\ r_{a_2} > r_2 > r_c$$

Equations 1, 2 and 3, 4 are the travelling field waves which an electron, which is emitted from either the inner or the outer cathodes respectively, will interact with. The important component is the $l=1$ component since the electrons should travel with the velocity of this component and in proper phase with respect to it so that energy exchange can take place to produce electronic conductance or susceptance.

The equations of motion of the electrons in the magnetron can be written

$$(5) \quad \dot{r} + \Omega \theta r - \dot{r} \theta^2 = \frac{|e|}{m} + \frac{dV}{dr} - \frac{|e|}{m} E_r(r, \theta, t)$$

$$(6) \quad \frac{d}{dt} r \theta - \Omega r = - \frac{|e|}{m} E_\theta(r, \theta, t)$$

where

$$35 \quad \frac{\Omega}{2\pi} = \frac{|e| H}{2\pi m} = \text{cyclotron frequency.}$$

$\frac{dV}{dr}$ = static electric field between cathode and vane tips.

For the central cathode space,

$$(7) \quad r_1 = \frac{\frac{|e|}{m} E_0 (g_1)_l^n \left(\frac{r_1}{r_{a_1}} \right)^{nl-1} \cos nl\alpha}{\Omega - \frac{2\omega_n}{nl}}$$

For the inverted magnetron space

$$50 \quad (8) \quad r_{a_2} = \frac{\frac{|e|}{m} E_0 (g_2)_l^n [LJ'_{nl} + MN'_{nl}] \cos nl\alpha}{\Omega + \frac{2\omega_n}{nl}}$$

where α is the angle of lead or lag of the electron with respect to the lth wave. For various regions of $nl\alpha$, the electrons will either move toward the vane tips or will move toward the cathode. Thus bunching can take place in either region.

The oscillating electric field may be described by the vector potential $\mathbf{A}(r, t)$ where

$$(9) \quad \vec{E} = - \vec{A}$$

where $(\vec{A})$ denotes a vector, and where the dot denotes partial differentiation with respect to time. Then the following equation must be satisfied:

$$(10) \quad \Delta \times \Delta \times \vec{A} + \epsilon \mu \vec{A} = \mu \rho \vec{V}$$

(see Stratton, Electromagnetic Theory) where $\vec{V}$ is the current density. Solutions of Equation 10 exist in the form

$$(11) \quad \vec{A}(r, t) = A_{0n}(r) e^{i\omega_n t}$$

If the manipulations are carried through, using a perturbation method of solution,

$$(12) \quad \omega_n' = -\frac{\iint v \cdot A_{0n}^* r dr d\theta}{2\epsilon\omega_n \iint A_{0n} \cdot A_{0n}^* r dr d\theta}$$

from which,

$$(13) \quad \Delta\omega = -R.P. \frac{\iint v \cdot A_{0n}^* r dr d\theta}{2\epsilon\omega_n \iint A_{0n} \cdot A_{0n}^* r dr d\theta}$$

$$(14) \quad \frac{\omega_n}{2Q_0} = -I.P. \frac{\iint v \cdot A_{0n}^* r dr d\theta}{2\epsilon\omega_n \iint |A_{0n}|^2 r dr d\theta}$$

see Smith and Shulman "Frequency Modulation and Control by Electron Beams." Proceedings of I. R. E., July 1947,

where

$$\frac{\Delta\omega}{2\pi}$$

is the change in frequency due to injected electrons, Q_0 is the Q of the cavity with the injected electrons, and the magnetron is operating in the

$$n = \frac{N}{2} \text{ mode}$$

A_{0n}^* is the conjugate of the vector potential, and R. P. and I. P. means the real part and imaginary parts, respectively.

Equation 13 represents a small quantity due to the fact that it is calculated from the unperturbed field but is valid and suitable for this discussion. Substituting Equations 1 and 2 for the central cathode regions into Equations 11 and 12, the frequency change in this central cathode region may be approximated as

$$(15) \quad \Delta\omega \approx \frac{I_a \left(g_1 \right)_l^n \int_{r_0}^{r_{a_1}} \left(\frac{r_1}{r_{a_1}} \right)^{n|l|} \sin nlr dr}{E_0 4\pi\epsilon r_{a_1} \sum_{l=-\infty}^{\infty} \frac{\left(g_1 \right)_l^{n^2}}{n|l|}}$$

which shows that the pushing is a function of I_a , which is the current, and of the static field conditions.

It is convenient, however, to perform this pushing or loading in the inverted magnetron structure region where the static field conditions may be approximated and where the oscillating field is produced by the central cathode structure.

Comparing Equations 3 and 4 with Equations 1 and 2, it is seen that the oscillating field falls off less rapidly in passing from the outer vane tips to the outer cathode than in passing from the inner vane tips to the central cathode. Since the current may be made large due to the large surface of the outer cathode and due to the fact that bunching may take place in the region between the outer vane tips and the outer cathode, see Equation 8, an expression similar to Equation 15 which may be derived for this region will show that high pushing or high loading may be achieved depending on the value of a . This angle will be controlled by suitable choices of E_0 , which is determined by the power into the central cathode region, the magnetic field intensity H , and the direct current radial field between the outer vane tips and the outer cathode. Once the control parameters are suitably chosen, the

use of the grid in the outer cathode structure will permit further control of the frequency change of the energy absorption.

Some care must be taken that the modulating structure does not break into oscillation with applied modulating signals due to the interactions in the inverted magnetron structure region. However, this condition is rather unlikely since the inverted magnetron is not a good oscillator due to the fact that the modes of oscillation may overlap and inefficient energy exchange will take place.

Thus the invention described comprises an improved method of and means for modulating either the frequency or the amplitude, or both, of a microwave magnetron generator wherein a second electron-emissive cathode is disposed around the periphery of a portion of the magnetron anode cavity vane tips. Electron emission from the outer cathode interacts with the microwave electric fields established within the magnetron cavity resonators, thus inducing out-of-phase currents in the anode cavity vanes which react upon the generated oscillations. The type and degree of modulation is dependent upon the operating voltages applied to the various elements of the device and to the intensity of the applied axial magnetic field relative to the frequency of the generated oscillations. Modulating signals are applied to the auxiliary electron beam generating means to control the amount of electron emission therefrom which impinges upon the anode vane tips. A grid-controlled beam-type modulating structure is disclosed for providing improved control by the applied modulating signals. A practical structure comprising a modification of an existing type magnetron tube is disclosed.

I claim as my invention:

40 1. A magnetron microwave generator including a first electron-emissive cathode, an anode disposed adjacent said cathode, means adjacent said anode for subjecting electrons from said cathode to a substantially constant intensity transverse magnetic field, means connected to said cathode and said anode for applying operating potentials thereto to generate microwave oscillations on said anode, a second electron-emissive cathode surrounding a portion of said anode, shielding means interposed between said second cathode and the remainder of said anode for directing electrons emitted by said second cathode to impinge upon said anode portion, and means connected to said second cathode and said anode for applying modulating potentials thereto for controlling said directed electrons to modulate said oscillations.

2. A magnetron microwave generating system including a first electron-emissive cathode, an anode disposed adjacent said cathode, means for subjecting electrons from said cathode to a substantially constant intensity magnetic field, means for applying operating potentials to said anode and cathode to generate microwave oscillations on said anode, a second electron-emissive cathode surrounding a portion of said anode, shielding means interposed between said second cathode and the remainder of said anode for directing electrons emitted by said second cathode to impinge upon said anode portion in a direction substantially transverse to said magnetic field, and means for controlling said directed electrons to modulate said oscillations.

3. A magnetron microwave generating sys-

tem including an electron-emissive cathode, an anode disposed adjacent said cathode, means for subjecting electrons from said cathode to a substantially constant intensity transverse magnetic field, means for applying operating potentials to said anode and cathode to generate microwave oscillations on said anode, an electron source surrounding a portion of said anode, means connected to said source for directing electrons emitted by said source to impinge upon said anode, means for subjecting the electrons from said source to a transverse magnetic field of such intensity that said electrons do not absorb energy from said microwave oscillations during a cycle of said oscillations, whereby said electrons constitute a pure reactive load on said anode, and modulation signal input means connected to said electron source for controlling said directed electrons to modulate the frequency of said oscillations.

4. A magnetron microwave generating system including an electron-emissive cathode, an anode disposed adjacent said cathode, means for subjecting electrons from said cathode to a substantially constant intensity transverse magnetic field, means for applying operating potentials to said anode and cathode to generate microwave oscillations on said anode, an electron source surrounding a portion of said anode, means connected to said source for directing electrons emitted by said source to impinge upon said anode, means for subjecting the electrons from said source to a transverse magnetic field of such intensity that said electrons absorb energy from said microwave oscillations, and modulation signal input means connected to said electron source for controlling said directed electrons to modulate the amplitude of said oscillations.

5. A magnetron microwave generator including a first electron-emissive cathode, a plurality of radially disposed cavity resonator anodes disposed around and adjacent to said cathode, means adjacent said anode for subjecting electrons from said cathode to a substantially constant intensity transverse magnetic field, means connected to said cathode and said anode for applying operating potentials thereto to generate microwave oscillations in said resonator anodes, a second electron-emissive cathode surrounding a portion of said anodes, shielding means interposed between said second cathode and the remainder of said anodes for directing electrons emitted by said second cathode to impinge upon said portion of said anodes, and means connected to said second cathode and said anode for applying modulating potentials thereto for controlling said directed electrons to modulate said oscillations.

6. A magnetron microwave generating system including a first electron-emissive cathode, a plurality of radially disposed cavity resonator anodes disposed around and adjacent to said cathode, means for subjecting electrons from said cathode to a substantially constant intensity magnetic field, means for applying operating potentials to said anodes and cathode to generate microwave oscillations in said resonator anodes, a second electron-emissive cathode surrounding a portion of said anodes, shielding means interposed between said second cathode and the remainder of said anodes for directing electrons emitted by said second cathode to impinge upon said portion of said anodes in a direction transverse to said magnetic field, and

means for controlling said directed electrons to modulate said oscillations.

7. A magnetron microwave generating system including a first electron-emissive cathode, a plurality of radially disposed cavity resonator anodes disposed around and adjacent to said cathode, means for subjecting electrons from said cathode to a substantially constant intensity transverse magnetic field, means for applying operating potentials to said anodes and cathode to generate microwave oscillations in said resonator anodes, a plurality of electron beam sources surrounding a portion of said anodes, shielding means interposed between said sources and the remainder of said anodes for directing electrons emitted by each of said sources to impinge upon said portion of said anodes, and means for controlling said directed electrons to modulate said oscillations.

8. A tube including a first electron-emissive cathode, a plurality of radially disposed conductive anodes disposed around said cathode, adjacent ones of said anodes forming a plurality of cavity resonators and each of said anodes including a projecting portion substantially separate from said resonators, a second electron-emissive cathode surrounding said projecting portions of said anodes and shielding means interposed between said second cathode and the remainder of said anodes for directing electrons emitted by said second cathode to impinge upon said projecting portions of said anodes.

9. A microwave tube including a first electron-emissive cathode, a plurality of radially disposed conductive anodes disposed around said cathode, a plurality of conductive elements connecting together alternate ones of said anodes, adjacent ones of said anodes forming a plurality of cavity resonators and each of said anodes including a projecting portion substantially separate from said resonators, a second electron-emissive cathode surrounding said projecting portions of said anodes and shielding means interposed between said second cathode and the remainder of said anodes for directing electrons emitted by said second cathode to impinge upon said projecting portions of said anodes.

10. A microwave tube including a first electron-emissive cathode, a plurality of radially disposed conductive anodes disposed around said cathode, adjacent ones of said anodes forming a plurality of cavity resonators and each of said anodes including a projecting portion substantially separate from said resonators, a second electron-emissive cathode surrounding said projecting portions of said anodes and shielding means interposed between said second cathode and the remainder of said anodes for directing electrons emitted by said second cathode to impinge upon said projecting portions of said anodes.

11. A microwave tube including a first electron-emissive cathode, a plurality of radially disposed conductive anodes disposed around said cathode, adjacent ones of said anodes forming a plurality of cavity resonators and each of said anodes including a projecting portion substantially separate from said resonators, a plurality of electron beam sources surrounding said projecting portions of said anodes, shielding means interposed between said sources and the remainder of said anodes for directing electrons emitted by each of said sources to impinge upon one of said projecting portions of said anodes.

12. A magnetron microwave generating system including a first electron-emissive cathode, a plurality of radially disposed conductive anodes dis-

posed adjacent said cathode, adjacent ones of said anodes forming a plurality of cavity resonators and each of said anodes including a projecting portion substantially separate from said resonators, means for subjecting electrons emitted from said cathode to a substantially constant intensity magnetic field, means for applying operating potentials to said anodes and cathode to generate microwave oscillations on said anodes and in said resonators, a second electron-emissive cathode surrounding said projecting portions of said anodes and effectively isolated from said resonators, shielding means interposed between said second cathode and the remainder of said anodes for directing electrons emitted by said second cathode to impinge upon said projecting portions of said anodes in a direction transverse to said magnetic field to interact with said oscillations on said anodes, and means for controlling said directed electrons to modulate said oscillations.

13. A magnetron microwave generating system including a first electron-emissive cathode, a plurality of radially disposed conductive anodes disposed adjacent said cathode, adjacent ones of said anodes forming a plurality of substantially parallel disposed cavity resonators operative in axial modes, means for subjecting electrons emitted from said cathode to an axial substantially constant intensity magnetic field, means for applying operating potentials to said anodes and cathode to generate microwave oscillations on said anodes and in said resonators, a second electron-emissive cathode surrounding said anodes and operative upon the traveling microwave field on the peripheries of said anodes, shielding means interposed between said second cathode and the remainder of said anodes for directing electrons emitted by said second cathode to impinge upon said peripheral portions of said anodes in a direction transverse to said magnetic field to interact with said traveling microwave fields thereon, and means for controlling said directed electrons to modulate said oscillations.

14. A microwave tube including a first electron-emissive cathode, a plurality of radially disposed conductive anodes disposed around said cathode, adjacent ones of said anodes forming a plurality of radially disposed cavity resonators and each of said anodes including an axially projecting portion substantially separate from said resonators, a second electron-emissive cathode surrounding said projecting portions of said anodes, a support for said second cathode interposed between said second cathode and the remainder of said anodes and effectively shielding electron emission from said second cathode from the microwave fields within said resonators and for directing electrons emitted by said second cathode to impinge upon said projecting portions of said anodes.

15. A magnetron microwave generating system including a first electron-emissive cathode, a plurality of radially disposed conductive anodes

alternately connected together and disposed adjacent said cathode, adjacent ones of said anodes forming a plurality of radially disposed cavity resonators and each of said anodes including an axially projecting portion substantially separate from said resonators, means for subjecting electrons emitted from said cathode to a substantially constant intensity magnetic field, means for applying operating potentials to said anodes and cathode to establish microwave fields between said projecting portions of adjacent ones of said anodes and in said resonators, a second electron-emissive cathode surrounding said projecting portions of said anodes and shielding means interposed between said second cathode and the remainder of said anodes for directing electrons emitted by said second cathode to impinge upon said projecting portions of said anodes in a direction transverse to said magnetic field to interact with said fields between said projecting portions of said anodes, and means for controlling simultaneously the energy of said directed electrons to modulate said oscillations.

16. A microwave tube comprising a central cathode, an anode surrounding said cathode and comprising axially extending portions and radially extending portions, a second cathode insulated from said central cathode and said anode and surrounding said axially extending portions of said anode and a shield interposed between said second cathode and said radially extending portions of said anode.

17. A tube according to claim 16 including means connected to said anode and cathodes for applying separate operating potentials thereto and means adjacent said anode for applying an axial magnetic field to said cathodes and anode.

18. A microwave tube comprising an elongated central cathode, an anode comprising a plurality of conductive vanes surrounding said cathode, each of said vanes comprising a radially extending portion and an axially extending portion, adjacent ones of said vanes forming cavity resonators tuned to the operating microwave frequency, a second cathode surrounding said axially extending portions, a shield interposed between said second cathode and said radially extending portions, means connected to said anode and cathodes for applying separate operating potentials thereto, and means adjacent said anode for applying an axial magnetic field to said cathodes and anode.

CARMEN L. CUCCIA.
